(57) **CLAIM**

The ornamental design for a punch down tool handle, as shown and described.

DESCRIPTION

FIG. 1 is a left side view of the punch down tool handle of the present invention. The right side view is a mirror image of the left side view.

FIG. 2 is a front end view of the handle.

FIG. 3 is a rear end view of the handle.

FIG. 4 is a top view of the handle; and,

FIG. 5 is a bottom plan view of the handle.
